UNITED STATES PATENT OFFICE

EDMUND C. POHLAND, AUGUST F. POHLAND, AND CHARLES POHLAND, SR., OF
LATROBE, PENNSYLVANIA

WINDOW-SASH MULLION

Application filed June 19, 1928. Serial No. 286,666.

This invention relates to window sash mullions and particularly to the construction of the mullions and of the joints at their intersections.

5 An object of this invention is to provide a window sash having mullions and cross mullions joined together to provide a plurality of light spaces, each mullion being formed of a single strip of material.

10 Another object is to provide window sash mullions, which when joined together, are extremely rigid and will not spread and leave the glass loose in the frames.

15 A further object is to simplify the construction of the mullions and the joints at the intersections of same, whereby less time will be required in the manufacture thereof, and the cost will be substantially reduced.

20 A further object is to provide novel means for joining together at predetermined spaced intervals, mullions of any cross sectional shape, so long as oppositely disposed ribs are formed on each mullion, one of such ribs being used to provide means for retaining a 25 pane of glass or the like between the mullions and cross mullions.

25 Other objects and advantages of our invention will become apparent from the following description.

30 In the drawings we have shown preferred embodiments of our invention. In this showing:

35 Figure 1 is a front elevation of a window sash provided at the top thereof with horizontal and vertical mullions, and at the bottom with angularly disposed mullions.

40 Figure 2 is a front elevation of a window sash having arcuate shaped mullions therein.

45 Figure 3 is a perspective view of a mullion and cross mullion used in the construction shown in Figure 1.

Figure 4 is a bottom plan view of the construction shown in Figure 1.

50 Figure 5 is a top plan of the construction shown in Figure 1.

Figure 6 is a sectional view taken substantially on the line 6—6 of Figure 5, and,

55 Figure 7 is a perspective view of a mullion and cross mullion and of the construction of

the joint as used in the arcuate shaped mullions shown in Figure 2.

Heretofore, it has been customary among window sash manufacturers to form one mullion of a single strip, a plurality of the single strips being arranged either vertically or horizontally within a window sash. The cross mullion however, was formed of a plurality of sections joined to the single strip mullions at spaced intervals. This construction was found to be disadvantageous in that the finished structure was not sufficiently rigid, and would spread at the joints whereby the glass would become loose in the frame. Of course, where there is only one mullion and cross mullion used in a sash, that is, where only one joint is to be formed between the mullions, single strips may be employed, but when it is necessary to form a plurality of joints it was found difficult to form cross mullions of single strips and at the same time provide a tightly fitting joint.

With the present invention the cross mullions may also be formed of a single strip and joined with the intersecting mullions at predetermined spaced intervals, without materially weakening the joints of the finished structure, a frame being provided which is rigid and in which panes of glass may be held with putty or like material, it having been found that the joints formed will not spread, regardless of the number of joints necessary.

The construction of the joint hereinafter shown may be used with mullions of any cross sectional shape where oppositely disposed ribs are provided on the mullion. Most of the present day constructions utilize an upper and lower rib to facilitate the placing of glass in proper position.

Referring to the drawings, the numeral 10 designates a mullion as a whole which may be placed in either vertical or horizontal position in a window sash. As shown in Figure 3 the mullion is provided with an upper rib 11, the sides thereof converging toward the top, and a lower rib 12 oppositely disposed from the rib 11, without converging sides, the width of the upper surface of the rib 11 being equal to the width of the rib 12. 100

The sides 13 of the mullion extend outwardly as shown in Figure 3 and a narrow ledge 14 is formed on the upper face of the side 13, between the edge thereof and the lower edge of the rib 11. A relatively wide lower ledge 15 is formed on the lower face of the side between the edge thereof and the lower rib 12, and a pane of glass or the like is adapted to be held in position against the ledge 15, as will be understood.

To form a tightly fitting joint between the mullion above described and a cross mullion of substantially the same cross sectional contour, it is necessary to cut the mullion in the following manner. The mullion 10 is cut vertically substantially half way through as shown at 16 in Figure 3, from the top of the rib 11, the width of the cut being equal to the width of the lower rib 12. After the downward cut has been made, the side portions adjacent the cut are bevelled as shown at 17, leaving the central portions 18 of substantially the same width, the width of each portion 18 being equal to the width of the lower rib 12. Adjacent each bevelled portion 17, the sides 13 are cut away from the lower extremity of the main cut 16 to the top of the ledge 14, substantially as shown at 19, whereby transverse cutaway portions 19' are provided adjacent the bevelled portions 17. Each side face 13 is then cut inwardly as shown at 20 the width of the cut being equal to the width of the rib 12, and a lower central portion 21 is left between and of the same width as the central portions 18.

It will be seen that the cut necessary to be made in the cross mullion will be different from that just described. The cross mullion 22, shown in Figure 3 is of substantially the same contour as the mullion 10, being provided with upper and lower ribs 23 and 24 respectively, and sides 25. The upper rib 23 converges upwardly and a small ledge 26 is formed corresponding to the ledge 14. A relatively wide ledge 26' is also formed corresponding to the ledge 15. The cross mullion 22 is cut substantially half way through from the bottom of the rib 24 as shown at 27, the width of the cut being equal to the width of the rib 12. Above the opening 27 the converging side faces of the upper rib 23 are bevelled as shown at 28, the central portion 29 between said portions 28 being left substantially the same width as the opening 27. From the outer extremity 30 of the bevelled portion 28 the sides 25 are cut parallel to the sides of the opening 27. The sides 25 are then cut transversely as shown at 31, the cut extending inwardly to the side face of the rib 24 as shown at 32. Central portions 32' are provided of a width equal to the width of the rib 24.

It will be obvious that the mullions and cross mullions may be cut at predetermined intervals and when it is desired to join them

together, the mullion 22 is placed with its cut out portion fitted into the cut out portion 16 of the mullion 10 and when properly fitted together the bevelled faces 28 of the mullion 22 engage the bevelled faces 17 of the mullion 10. The portions 29 engage the portions 18, the central portions 32' fit snugly against the sides of the rib 12, the transverse cut away portions 31 will engage the similar portions 19' and the central portion 21 will engage the upper central portion of the cut 27, whereby a neat and tightly fitting joint will result.

In the construction shown in Figure 7 the cuts are made similarly to those above described except that the cuts will be made at the desired angle, as will be apparent.

The above described construction provides mullions and cross mullions both of which may be formed of a single strip of material and may be joined together at predetermined intervals. The glass is adapted to be secured by putty in the usual manner, the frame will be rigid and will not spread whereby the glass will become loose. After the mullions have been joined together as shown in Figures 1 and 2, the outer frame or stile 35 may be secured in position.

The simple construction of the joints and the ease with which they may be assembled will materially reduce the cost of manufacture, and the structure may be made in half the time previously required. Furthermore, one man may easily secure the outside frame in position, where two or more were previously required, thus reducing the cost of labor.

It is to be understood that the forms of the invention herewith shown and described are to be taken as preferred examples of the same and that various changes in the shape, size and arrangement of parts may be resorted to without departing from the spirit of the invention or the scope of the subjoined claim.

We claim:

A joint for a bar and a cross-bar arranged in intersecting relation, said bar and cross-bar each being formed of a single strip of material, said bar and cross-bar being provided with oppositely disposed ribs and oppositely disposed side members, one of said ribs converging toward its outer extremity, said bar being provided with an opening extending substantially half way through from the top thereof and being further provided with an opening extending inwardly from each side member thereof, said last named openings communicating with said first named opening, said converging rib being beveled and cut away adjacent said first named opening and communicating with the latter and said second named openings, said side members being provided with relatively short longitudinal cut away portions communicating with the beveled portions of the ribs, and said cross-bar being provided with

an opening extending substantially half way through from the bottom thereof and being further provided with an opening extending inwardly from each side member thereof,
5 said last named openings communicating with said first named opening in the cross-bar, said converging rib of the cross-bar being beveled and cut away adjacent the openings in said cross-bar, and communicating
10 with the openings in said cross-bar, the side members of said cross-bar being provided with relatively short cut away portions communicating with the beveled portions on the ribs of the cross-bar, the openings, cut away portions and beveled portions of said cross-bar fitting with the openings, cut away portions and beveled portions respectively of
15 said bar.

In testimony whereof we affix our signatures.

EDMUND C. POHLAND.
AUGUST F. POHLAND.
